UNITED STATES PATENT OFFICE.

ELLSWORTH E. FLORA, OF CHICAGO, ILLINOIS, ASSIGNOR TO THE ZORGE SAFETY RAILWAY EQUIPMENT COMPANY, OF CHICAGO, ILLINOIS, A CORPORATION OF ILLINOIS.

SIGNAL MECHANISM.

No. 863,569.

Specification of Letters Patent.

Patented Aug. 13, 1907.

Application filed June 18, 1906. Serial No. 322,240.

To all whom it may concern:

Be it known that I, ELLSWORTH E. FLORA, a citizen of the United States, residing at Chicago, in the county of Cook and State of Illinois, have invented 5 new and useful Alarm and Signal Mechanism, of which the following is a specification.

This invention relates particularly to means for giving warning to an engineer, or motorman, approaching an open switch, or an open draw, with his train, or 10 car; and the primary object of the invention is to provide improved apparatus involving the use of a device which will be preparatorily set when the switch is thrown open and which will operate to detonate a torpedo, or explosive body, when a train passes over it in 15 approaching a switch.

The invention is illustrated in the accompanying drawings, in which—

Figure 1 is a diagrammatic view of a portion of a railway track equipped with this improved alarm device; 20 Fig. 2, a broken plan view showing a fragment of a rail and a portion of the mechanism of the improved alarm device in relation thereto; Fig. 3, a sectional view taken as indicated at line 3 of Fig. 2, and showing also a fragment of a car wheel; Fig. 4, a broken plan view showing on an enlarged scale the switch appearing at the right-hand portion of Fig. 1; Fig. 5, a sectional view taken as indicated at line 5 of Fig. 4; and Fig. 6, a broken section taken as indicated at line 6 of Fig. 5.

In the preferred construction, A represents the main 30 track of a railway; B, a side-track; C, a switch-point operated by any convenient means (not shown); D, a torpedo-placing device electrically connected with the switch-point and operating to cause an explosion, or a series of explosions in the event that a train passes over 35 the track in the direction indicated by the arrow while the switch-point is open; and D¹, a visual signal electrically connected with the device D.

The device D preferably comprises a casing d (Figs. 1, 2 and 3) having a lower chamber d¹ and an upper 40 chamber d², the chambers being separated by a plate d³ and the upper chamber having a removable top d⁴; a rotary torpedo-carrier d⁵ located in the upper chamber and having a depending sleeve d⁶ journaled in a bearing in the plate d³ and resting at its lower end on a spring- 45 casing d⁷ which is located in the lower portion of the chamber d¹; a shaft d⁸ extending through the sleeve d⁶ and into the casing d⁷, said shaft being connected by a stud d⁹ with a coil-spring d¹⁰ whose outer end is joined by studs d¹¹ to the casing d⁷; a ratchet-wheel d¹² fixed 50 on the upper end of the shaft d⁸; a pair of spring-held pawls d¹³ mounted on the carrier d⁵ and engaging the ratchet-wheel d¹²; a locking-lever d¹⁴ whose lower end is supported on a pivot d¹⁵ and whose upper end projects through a slot d¹⁶ in the plate d³, said locking-lever controlling 55 the movement of the carrier d⁵; a magnet d¹⁷

having an armature d¹⁸ controlling the movement of the locking lever d¹⁴; and an electric circuit d¹⁹ which indirectly controls the circuit of the magnet d¹⁷ and which is equipped with a battery d²⁰, said circuit d¹⁹ having a conductor d²¹ leading to a contact-point d²² 60 and a conductor d²³ connected with the switch-point C, and said circuit having also conductors d²⁴, d²⁵ connected with a train-actuated switch d²⁶. It is to be borne in mind that the mechanism D shown diagrammatically in Fig. 1 is, in practice, properly incased, as shown in 65 Figs. 2 and 3.

The mechanism D¹ comprises an electro-magnet d²⁷ included in the electric circuit d¹⁹ and normally energized by the battery d²⁰, a signal arm d²⁸ normally held in an elevated position by the magnet d²⁷, said arm d²⁸ 70 having a pivotal shaft d²⁹ on which is journaled a ratchet-wheel d³⁰ which serves to actuate a gear-train d³¹ of a governing device d³², said arm d²⁸ having a pawl d³³ through the medium of which the ratchet-wheel is actuated when the arm is raised through the medium of 75 the electro-magnet d²⁷; and an electric circuit d³⁴ in which the magnet d¹⁷ of the mechanism D is included, said circuit having a contact point d³⁵ engaging the arm d²⁸, when the latter is in its elevated position, and said circuit having a battery d³⁶ serving normally to energize 80 the magnet d¹⁷. The signal arm d²⁸ projects into a casing d³⁷ in which are mounted a lamp d³⁸ having a white light and a signal d³⁹ having a white surface. The signal arm d²⁸ is equipped with red glasses d⁴⁰, d⁴¹ adapted to cover the lamp d³⁸ and the signal d³⁹ when the arm 85 d²⁸ is dropped; the glass d⁴⁰ preferably being transparent and the glass d⁴¹ opaque. In the safety condition of the road, the lamp d³⁸ serves to give a clear light by night, and the signal d³⁹ serves to indicate safety conditions by day; and when the arm d²⁸ is lowered, the light from 90 the lamp passing through the glass d⁴⁰ indicates danger by night, and the red opaque glass d⁴¹ indicates danger by day.

From the description thus far given it will be understood that the visual signal will indicate danger in the 95 event that the electric circuit d¹⁹ is opened at the switch-point and at the train-actuated switch d²⁶; and also that the circuit d³⁴ will be broken and deenergize the magnet d¹⁷ of the torpedo-placing mechanism when the arm d²⁸ is lowered to indicate a visual danger signal. 100

The casing d may be of cylindrical form with one side made flat, or segmental, as indicated at g, to enable the casing to be placed close to a track-rail. The shaft d⁸ is journaled near the flat side of the casing, and the top d⁴ of the chamber d² is provided with an opening g¹ (Fig. 105 3) through which the torpedoes may be projected by the carrier and placed upon the adjacent rail of the track. The top d⁴ is preferably pivotally and removably connected with the body of the casing, the details of the connection being unimportant. The carrier d⁵ is 110

shown in the form of a disk equipped with two diametrically opposite sockets g^2 which serve to receive shanks g^3 of torpedoes g^4 . The shanks g^3 are provided at their ends with slots g^5 which receive clamping screws g^6 , whereby the torpedoes are firmly secured in place. The normal position of the torpedoes is shown in Fig. 2, from which it will be understood that the torpedoes lie normally parallel with the track-rail and housed in the chamber d^2 . The carrier d^3 is provided on its lower side with a pair of diametrically opposite locking shoulders g^7 arranged on a circle of given diameter, and on a diameter at right-angles to the diameter containing the shoulders g^7 and on a larger circle with diametrically opposite locking shoulders g^8 . The locking lever d^{14} is normally held in the position shown in Fig. 3 by the magnet d^{17} , in which position it is in the path of the stops g^8 and in engagement with one of said stops. A spring g^9 (Fig. 3) tends to throw the locking lever d^{14} to the other limit of its movement and thus bring the upper end of the locking lever into the path of the stops g^7 of the torpedo-carrier. When the magnet d^{17} is deenergized, as will occur when a breakage or failure of the electric circuit d^{19} occurs, the lever d^{14} will be actuated by the spring g^9 , thereby disengaging the lever from the stop g^8 with which it is in engagement and moving it into the path of the next succeeding stop g^7 , so that the torpedo-carrier will be permitted to make a quarter turn, thereby placing the torpedo above the track-rail at the point indicated at h in Fig. 2. Each torpedo-stem g^3 is formed with a head having, in the construction shown, three torpedoes mounted thereon, so arranged as to be presented longitudinally of the rail when in position for exploding, it being understood that the arrangement is designed to cause a series of explosions in rapid succession, when a wheel passes over the torpedoes.

In Fig. 1 is shown an electric circuit K provided with a bell k and a battery k^1 , said circuit being connected with the torpedo-carrier d^3 and with a contact point k^2 adapted to make contact with the spring d^{10} , shown in Fig. 3, when the latter expands in actuating the carrier. The purpose of the circuit K is to give a warning when the spring requires re-winding. The bell may be located at a station, if desired, so that an attendant can see that the device is re-wound. Ordinarily it is expected that it will be the duty of the train-crew to see that the device is re-charged after an alarm signal has been given.

The switch d^{26} of the electric circuit d^{19} is designed to break the circuit at the point where said switch is located when a train passes in the direction indicated by the arrow in Fig. 1, in which event, if the circuit d^{19} is also open at the contact point d^{22} the magnet d^{27} will be deenergized, a danger visual signal exhibited, the magnet d^{27} deenergized and a torpedo placed upon the track. Said switch preferably comprises a pair of spring contact members l , l^1 mounted upon an insulation block l^2 and connected, respectively, with the conductors d^{24} , d^{25} ; a casing l^3 within which the block l^2 is mounted on one lateral wall thereof with the spring contact members l , l^1 projecting horizontally into the casing; a contact member l^4 normally closing the circuit between the contact members l , l^1 and carried by an arm l^5 ; a vertical shaft, or stud, l^6 to which the arm l^5 is rigidly secured, said shaft l^6 being equipped at its

upper end with a head l^7 having groove-and-slot connections l^8 with the upper surface of the casing l^3 ; a torsion spring l^9 tending normally to hold the switch in the closed condition with the arm l^5 bearing against an internal stop l^{10} with which the casing l^3 is provided 70 and a wheel-actuated lever l^{11} connected by a transverse pivot l^{12} with lugs l^{13} with which the head l^7 of the stud l^6 is equipped, said lever being held normally in the position shown in Fig. 5 by a spring l^{14} . The lever l^{11} has a long arm l^{15} which is directed toward the switch-point C , and a short arm l^{16} which acts as a stop against an arm l^{17} with which the head l^7 is provided, thereby limiting the upward swing of the long end of the lever under the tension of the spring l^{14} . The free extremity of the long end of the lever is curved downwardly, as 80 shown in Fig. 5. The relation of the lever to the track-rail is shown in Fig. 4, from which it appears that the lever has an obliquely set lateral surface l^{18} forming a V-shaped space with the adjacent lateral surface of the tread portion of the rail, the surface l^{18} joining a surface 85 l^{19} parallel with and closely adjacent to the rail at the extremity of the long arm of the lever. It will now be understood that when a train passes in the direction indicated by the arrow in Fig. 4 the flange of the wheel will act as a wedge to turn the lever on its vertical axis, 90 thereby turning the shaft l^6 , actuating the arm l^5 and breaking the circuit d^{19} by withdrawing the contact member l^4 from between the contact members l , l^1 . When the train moves in the opposite direction from that indicated by the arrow, the wheels of the train 95 will oscillate the lever l^{11} in a vertical plane, but will not break the circuit at the switch d^{26} .

The operation of the mechanism hereinabove described may be briefly stated: Assuming the switch-point C to be closed, a train may pass over the track in 100 either direction without affecting the mechanism otherwise than by operating the switch d^{26} . Assuming the switch-point C to be open, a train passing over the track in the direction indicated by the arrow in Fig. 1 will operate the switch lever l^{11} , thereby breaking the 105 circuit d^{19} , so that the magnet d^{27} will be deenergized (since the circuit d^{19} is also broken at the contact point d^{22}), thereby permitting the arm d^{28} to drop and a danger visual signal to be exhibited, it being understood that in this movement the pawl d^{33} rides idly over the 110 ratchet-wheel d^{30} . When the arm d^{28} drops, the circuit d^{34} of the magnet d^{17} is broken, thereby deenergizing the magnet d^{17} and allowing the spring g^9 to move the locking lever d^{14} from the position shown in Fig. 3 to the other limit of its movement, where it will be in position to engage the succeeding stop g^7 . The spring d^{10} may now operate to turn the shaft d^8 and the ratchet-wheel d^{12} , which will, through the medium of the pawls d^{13} , turn the torpedo-carrier through an angle of 90° , or 115 until the stop g^7 engages the movable stop d^{14} . The relation of the casing d to the adjacent rail of the track is such that when the torpedo-carrier makes a quarter turn from the position shown in Fig. 2, a torpedo will be placed above the rail in position to be struck by a wheel of a passing train. The manner of supporting the casing 120 is not shown, but it will be understood that the casing is firmly supported in any suitable manner on the outer side of the adjacent rail, so that the stem of the torpedo will not be engaged by the flange of the wheel. After 125 operation of the device, the torpedo-carrier will, upon 130

closure of the circuit d^{19} , either at the switch C or at the train-actuated electric switch d^{26} , make a quarter revolution, owing to the fact that the arm d^{28} will be raised by the magnet d^{27} and the electric circuit d^{34} re-established,

5 lished, thereby causing the vibratory stop d^{14} to be retracted against the action of its spring. This will leave the device in a condition for a second operation. As has been indicated, however, train crews will be instructed to re-charge and re-set the device after each 10 operation; and where possible, warning will be conveyed by the circuit K to some attendant whose duty it is to keep watch of the signal mechanism.

It should be stated that the function of the governing device d^{32} is to prevent a rapid elevation of the arm d^{28} 15 when the magnet d^{27} is reenergized. It is to be borne in mind that the circuit d^{19} is momentarily closed during the intervals between the engagement of the lever l^{11} of the switch d^{26} by the wheels of the train; and with no provision made against the quick actuation of 20 the arm d^{28} and the re-establishment of the circuit d^{34} of the magnet d^{17} , the device D would be caused to operate to withdraw the torpedo from its position above the rail. The device d^{32} comprises a fan geared to the ratchet-wheel d^{30} , and the fan, operating at a high rate 25 of rotation, serves as a brake, insuring slow movement of the arm d^{28} . Therefore, before the circuit d^{34} can be re-established the circuit d^{19} is again broken by a succeeding wheel of the train, and this condition is maintained until the torpedo is encountered by the train. 30 It is noteworthy that the electric circuit d^{19} includes a branch which is connected with the switch-point C and a branch which is connected with the train-actuated electric switch d^{26} , the torpedo-placing device being located between said points.

35 The improved device may be usefully employed in connection with switches, draw-bridges, visual signals, crossings, and in various other situations.

What I regard as my invention, and desire to secure by Letters Patent, is—

1. The combination with a track-rail, a signaling device, 40 and an electric circuit controlling said signaling device, of a train-actuated switch-arm occupying a normally closed position in said circuit movable about a vertical axis and a wheel-actuated lever movable about a horizontal axis and serving to turn said switch-arm and break the 45 circuit when the train-movement is in one direction and to move idly without affecting the switch-arm when the train movement is in the other direction.

2. A train-actuated switch for the purpose set forth, 50 comprising a switch-arm, a vertical shaft on which said arm is secured, a spring tending to rotate said arm in one direction and close the circuit, a lever connected with said shaft by a horizontal pivot, said lever having a long arm with an oblique lateral surface, and a spring tending to hold the free end of said arm normally elevated. 55

3. The combination with a railway track of a torpedo-placing device, an electro-magnet controlling said device and having a circuit equipped with an electric generator, a visual signal, an electro-magnet controlling said signal, a circuit for said second-named electro-magnet controlled 60 from the track, and governing mechanism operated by said second-named electro-magnet and controlling the period of closure of said first-named circuit.

4. The combination with a railway track, of a torpedo-placing device, an electro-magnet controlling the same and 65 having a circuit equipped with an electric generator, a visual signal having a movable member connected with said electric circuit and equipped with a governing device controlling the closing of said circuit, an electro-magnet serving to actuate said movable member of the 70 visual signal, and a circuit for said second-named magnet equipped with a generator and controlled by a movable rail of the track placed on one side of the torpedo-placing device and a train-actuated electric switch placed on the other side of the torpedo-placing device.

ELLSWORTH E. FLORA.

In presence of—
L. HEISLAR,
J. H. LANDES.
